UNITED STATES PATENT OFFICE.

LOUIS H. VOTE, OF MUNHALL, PENNSYLVANIA.

BOTTLE CAPPER.

1,410,278.

Specification of Letters Patent. Patented Mar. 21, 1922.

Application filed August 27, 1920. Serial No. 406,346.

To all whom it may concern:

Be it known that I, Louis H. Vote, a citizen of the United States, residing at Munhall, in the county of Allegheny and 5 State of Pennsylvania, have invented new and useful Improvements in Bottle Cappers, of which the following is a specification.

This invention relates to capping devices, and more particularly to a device specially 10 adapted for securing crimp caps on bottles.

One of the main objects of the invention is to provide a device of the character stated of simple construction and operation which may be readily produced and sold at small 15 cost. A further object is to provide a device which may be readily adjusted to accommodate bottles of different height. Further objects will appear from the detailed description.

20 In the drawings:—

Figure 1 is a side view of the device as used.

Figure 2 is a top plan view.

25 Figure 3 is a section taken substantially on line 4—4 of Figure 1.

Figure 4 is a detail sectional view of the nut.

An upright 1 is secured in any suitable manner in a base 2 and has its upper end 30 portion threaded at 3 to receive a nut 4 provided with diametrically opposite arms 5, these arms facilitating turning of the nut for adjusting the same on the standard. A capping lever 6 is provided at its inner end 35 with a central slot 7 forming arms 8 which are adapted to fit beneath nut 4 when the lever is placed in operative relation to standard 1, this lever not being connected to either the nut or the standard. This lever is pro- 40 vided a short distance from its inner end with a capping member 9 of substantial cup shape which is secured by a rivet 10 or in any other suitable manner to the under face of lever 6. A cushion member 11, such as 45 a disc of rubber or other suitable material is positioned between member 9 and lever 6, the function of this cushion member being to prevent breakage of a bottle by exerting too great pressure upon lever 6.

50 In practice, the bottle B is placed upon block 2, and crimp cap C is placed upon the upper end of the neck of the bottle, after which the lever 6 is placed in operative position about standard 1 so as to position member 9 over cap C, nut 4 being adjusted on

the standard so that by exerting downward pressure upon the outer arm of the lever member 6 member 9 is forced downwardly over cap C so as to compress the same and secure it about and beneath the usual bead d 60 at the upper end of the bottle neck. Nut 4 may be readily adjusted upon the standard 1 to accommodate bottles of different heights, and the cushion member 11 eliminates breakage of the bottle due to excessive pressure 65 being exerted on the cap C such as would be apt to occur if this cushion member were omitted.

In applying the cap the pressure should be evenly distributed so as to cause the cork 70 disc in the cap to fit tightly against the entire upper edge of bead d thus insuring tight closure. To accomplish this the nut 4 is so adjusted that the member 9 will fit snugly upon the upper end of the neck of 75 bottle b. This adjustment may be readily effected by turning the nut up upon standard 1, lever 6 being then so placed that member 9 fits snugly over the bottle neck, after which nut 4 is turned down so as to contact 80 with the upper face of the lever. The cap is then applied in the manner above described, and this adjustment of the lever insures that the cap is forced into tight contact with the complete periphery of the upper edge of the bottle neck. This adjustment may be readily effected, and the set of the lever may be quickly and easily made to accommodate bottles of different heights. This 85 provides a very simple and inexpensive de- 90 vice composed of a minimum of parts and which may be readily adjusted so as to insure proper positioning of cap c upon the bottle.

As will be noted more clearly from Figure 95 1, the underface of nut 4 is rounded so that arms 8 of lever 6 are free to rock upon this face, thus permitting the lever to be readily formed from a strip of flat material.

What I claim is:—

In a device of the character described, a standard, a nut threaded on said standard, a flat lever bifurcated at one end to provide arms fitting about the standard and beneath the nut, the underface of said nut being 105 rounded, and a cap compressing member carried by said lever.

In testimony whereof I affix my signature.

LOUIS H. VOTE.
